Erastus Blakeslee, of New Haven Conn.

Des. 2028

Letters Patent No. 2028-Dated Feby 7-1865.

Design for a Military Button Hook.

The schedule referred to in these Letters Patent and making part of the same.

1. Description, as may concern:

Be it known that of Erastus Blakeslee, of New Haven, in the County of New Haven, and State of Connecticut, have invented or produced a new and original design for a Military Belt Hook, and I do hereby declare the following to be a full, clear and exact description of the same, when taken in connection with the accompanying drawings and the letters of reference marked thereon, and which said drawings constitute part of this specification, and represent:

Fig 1 a front view, and in

Fig 2 an edge view, in both figures represented as attached to, and hooked in a belt.

My design relates to an improvement in the hook used for clasping the belt around the body of soldiers in the service of the United States, its object being to produce a clasp at much less cost, more convenient for the wearer, smaller and equally "dresy".

Heretofore hooks for this purpose have been constructed by soldering a hook onto the back side of a large metallic (square) plate, their form rendering it inconvenient for the wearer to adjust his belt, and being so large were heavy and proportionately costly.

DES. 2028

2

To produce my design I cut from a sheet of brass or other
suitable metal in the form of a cross as seen in fig 1, the three
arms on the cross are a piece and secured by rivets by which to secure it
to the belt. The other arm C, formed longer as denoted in
fig 1. This arm C is bent as denoted in fig 2, to form a hook
to catch into the holes in the end B of the belt. I stamp or
otherwise fix the letters E. S. upon the face, polishing or
otherwise finishing the hook, when finished the four arms are
nearly alike. Thus I have produced a hook, more convenient and
about one third the weight of the common hook.

Having fully described and illustrated my design, what I
claim and desire to secure by Letters Patent is The design for a belt
hook as shown and described.
